UNITED STATES PATENT OFFICE

162,121

KNIFE SHARPENER

Charles E. Branick, Fargo, N. Dak.

Application April 19, 1950, Serial No. 9,340

Term of patent 14 years

(Cl. D37—1)

To all whom it may concern:

Be it known that I, Charles E. Branick, a citizen of the United States, residing at Fargo, in the county of Cass and State of North Dakota, have invented a new, original, and ornamental Design for a Knife Sharpener, of which the following is a specification, reference being had to the accompanying drawing, forming part thereof.

Referring to the drawing:

Fig. 1 is a perspective view of a knife sharpener illustrating my novel design, the same being viewed from the front and one side;

Fig. 2 is a view in perspective as seen from the rear and one side; and

Fig. 3 is a view in rear elevation.

I claim:

The ornamental design for a knife sharpener, as shown.

CHARLES E. BRANICK.
